COMBINED FLASHLIGHT CLAMP AND
MOUNTING BRACKET THEREFOR

David Mitchell, Jr., Rosemead, Calif.

Application May 31, 1950, Serial No. 10,276

Term of patent 3½ years

(Cl. D48—24)

To all whom it may concern:

Be it known that I, David Mitchell, Jr., a citizen of the United States, residing at Rosemead, in the county of Los Angeles and State of California, have invented a new, original, and ornamental Design for a Combined Flashlight Clamp and Mounting Bracket Therefor, of which the following is a specification, reference being had to the accompanying drawing forming part thereof.

In the drawing:

Figure 1 is a perspective view of a combined flashlight clamp and mounting bracket therefor, showing my new design.

Figure 2 is an end elevation of the article as viewed from the right in Figure 1.

Figure 3 is a front elevation as viewed from the right in Figure 2.

The broken lines shown in the drawing are for illustrative purposes only.

I claim:

The ornamental design for a combined flashlight clamp and mounting bracket therefor, substantially as shown and described.

DAVID MITCHELL, JR.
